UNITED STATES PATENT OFFICE.

FRANKLIN B. GIESLER, OF MILWAUKEE, WISCONSIN.

FLUID-PRESSURE CUT-OFF.

SPECIFICATION forming part of Letters Patent No. 596,433, dated December 28, 1897.

Application filed January 28, 1897. Serial No. 621,039. (No model.)

To all whom it may concern:

Be it known that I, FRANKLIN B. GIESLER, a citizen of the United States, and a resident of Milwaukee, in the county of Milwaukee 5 and State of Wisconsin, have invented certain new and useful Improvements in Cut-Offs; and I do hereby declare that the following is a full, clear, and exact description thereof.

10 My invention has for its main object to provide a simple economical means for automatically stopping the flow of a fluid under pressure to an apparatus or circulating system the instant a leak of any importance may 15 occur, and it also contemplates a similar result incidental to manual operation of suitable mechanism, provision being made to prevent the ram that would otherwise take place incidental to sudden cessation of said 20 flow. Hence said invention consists in certain peculiarities of construction and combination of parts hereinafter set forth with reference to the accompanying drawings and subsequently claimed.

25 Figure 1 of the drawings represents a vertical transverse section of my device, the plane of the section being indicated by line 1 1 in Fig. 3; Fig. 2, an elevation, partly in section, on the irregular plane indicated by 30 line 2 2 in the preceding figure; Figs. 3 and 4, plan views, partly in horizontal section, these views being respectively indicated by lines 3 3 and 4 4 in Fig. 1.

Referring by letter to the drawings, A represents a casing constituting a coupling for 35 connecting a feeder of steam, ammonia, or other fluid under pressure with an apparatus or pipe system in which the fluid may be circulated. A horizontal partition *b*, provided 40 with a valve-seat aperture *c*, is arranged intermediate of the inlet-nozzle *d* and outlet-nozzle *e* of the casing. A hollow protuberance *f* of the casing below the inlet-nozzle *d* thereof contains a cylindrical plug *B*, provided 45 with a passage *g*, that is brought in and out of register with ports *h* *i*, connecting the bore of said protuberance with said inlet-nozzle and the outlet-nozzle of said casing. The stem *j* of the plug turns in a stuffing- 50 box gland *k*, set in the protuberance of the casing, and a handle *m* is made fast to said stem.

From the foregoing it will be understood

that provision is made for a by-pass at will between the inlet-nozzle and outlet-nozzle of 55 the casing, the purpose of this by-pass being hereinafter set forth in connection with the term "engineer's valve," employed to comprehend the plug *B* and its handle.

A valve *C*, corresponding to the seat portion of the aperture *c* in partition *b* of the casing *A*, has a plurality of depending arms *n*, connected to a preferably hollow cone *D*, and these arms are guided in said aperture. By having the cone hollow the same is lighter 65 than it would be otherwise. The valve *C* has its play in the chamber portion of the casing *A* above partition *b*, and the stem *E* of this valve has play in a stuffing-box gland *o*, set in the detachable top *F* of said casing. The 70 top is bolted to the body of the casing, and the joint between the two is sufficiently tight to prevent leak of the fluid under pressure.

To increase the bearing for the valve-stem *E*, the casing-top is provided with an upwardly-extending boss *p*, that is herein shown as being reduced for a portion of its length, the purpose of this reduction being herein- 75 after set forth.

Surrounding the boss *p* is a shell *G*, having 80 a bottom flange held to the casing-top by means of screws, and the the valve-stem *E*, extending up through said boss, comes within the bore *r* of the shell, this bore being terminated a limited distance below the shell-top 85 within an annular space *s*, having communication with a port *t*, leading up from the aforesaid chamber portion of the casing.

A vent-port *u* leads from the shell-bore into a chambered fitting *H*, provided with vertically-disposed pop-valves *v* *w*, both of which open in the same direction, and the top of the shell is provided with a seat-opening *x*, that is normally closed by a plunger *I*, having its upper end beveled to correspond with the 90 seat portion of said opening in which it fits. The plunger is centered in the upper end of the shell-bore above the vent-port *u*, and seated on the top of the shell is a spiral spring *J*, under compression against a plate *K*, loosely 95 engaged by the stem *L* of said plunger, this plate being held in vertically-adjusted position by a nut *y* and a jam-nut *z*, run on the screw-threaded upper end of the plunger- 100 stem. 105

The upper end of the valve-stem *E* is shown

reduced to form a shoulder, on which a piston M is seated, and this piston is held to its seat by means of a clamp-nut N, run on a screw-thread cut upon the reduced end of said stem. 5 The piston is shown as having a beveled upper edge, and a correspondingly - beveled shoulder in the shell-bore constitutes a stop for limiting the upward stroke of said piston, the latter being shown as having a depending 10 flange flared upon the interior thereof to thereby gradually decrease thickness in a downward direction, and fluid under pressure within this flange tends to spread the same in an outward direction, whereby a sufficiently 15 tight fit is maintained in said shell - bore, clearance for said piston on its downstroke being had by reason of the reduced portion of boss p on casing-top F being proportioned to come within the piston-flange when said 20 stroke occurs.

A passage b', leading from the outlet-nozzle e of the casing up through the latter and its top, has communication with that portion of the shell-bore containing piston M in order 25 that some of the fluid under pressure that has passed valve C may operate against said piston to support said valve away from its seat, and while any suitable means may be employed to establish this communication 30 preference is given to a connection having a stop-cock, through which the said fluid may be cut off at will and that remaining in said shell-bore readily exhausted. As herein shown, the connection above inferred may be a three- 35 way stop-cock connected by nipples with the casing-top F and shell G, the stem c' of a hollow plug P, constituting part of the three-way cock, being rotative in a stuffing-box gland d' and made fast to a long and short arm bell- 40 crank.

The short arm Q of the bell-crank carries a weight R and is normally at rest against a stop e', extending from the stuffing-box gland d', engaged by the stem c' of hollow plug P, 45 constituting part of the three-way stop-cock. The long arm S of the bell-crank is shown connected to a cable T, that may lead to any convenient point more or less distant from the stop-cock, this cable serving as a convenient 50 means to actuate said bell-crank against resistance of said weight.

A port F' of the hollow plug P is normally open to the passage b' in the casing, and another port g' of said plug is normally out of 55 register with an exhaust-port h', pertaining to the chamber in which the aforesaid plug has its rotary movement. A pipe U, fitted in the latter port, may lead to any convenient point for exhaust of fluid under pressure from 60 the bore of shell G above specified.

In practice all the working parts above specified are normally in position best shown in Fig. 1, and should an important leak occur in the apparatus or circulating system connected to the outlet of casing A there will be 65 a reduction of pressure ahead of the valve C, as well as in the shell-bore under the piston

M. Therefore said valve will instantly find its seat by gravity, aided by the velocity of the fluid under pressure exerted upon the aforesaid valve and the exterior of the cone in suspension therefrom. This instant automatic cut-off is of especial value in connection with the use of ammonia for the reduction of temperature, as thereby the diffusion 75 of fumes dangerous to life is prevented. The same result may be obtained by cutting off the main volume of the fluid under pressure from the shell-bore and permitting the ready exhaust of so much of said fluid as may remain 80 in said bore under the piston on the valve-stem, this operation being effected in times of emergency or whenever it may be found desirable to test the working of the valve. By employing the cone D the surface area 85 exposed to steam is increased, and thus operation of the valve is facilitated. The weight-and-crank-controlled three - way stop - cock above specified constitutes a ready means for effecting the instant automatic seating of the 90 cut-off valve at will, it being understood that the movement of the bell-crank to lift the weight will cause a partial rotation of hollow plug P to bring its port f' away from the passage b' in casing A and the other port g' 95 opposite the exhaust. On release of the bell-crank the hollow plug is automatically brought to normal position incidental to the limited descent of weight K, carried by the short arm of said crank.

On descent of the valve C the pop-valve w opens to prevent formation of a vacuum above piston M, and when said valve is lifted the pop-valve v opens to prevent an air-cushion against said piston.

When the valve C finds its seat, as above described, the back pressure operating upon the plunger I retracts the latter against the resistance of spring J away from the opening x in the top of shell G, to thereby prevent the ram that would otherwise occur, said plunger being thereafter automatically returned to normal position by expansion of said spring. It will also be understood that pop-valve v opens as the plunger descends, thus preventing an air resistance when this descent takes place. The valve C having been seated, it is necessary to open the engineer's valve in order that the fluid under pressure may operate upon the former valve, to thus open the partition-aperture intermediate of the casing inlet and outlet. At the same time some of the fluid under pressure will find its way into the shell-bore under piston M, to thereby support said valve away from its seat for an indefinite 125 period, the engineer's valve being closed when the automatic lifting of the cut-off valve C has been accomplished.

The proportions of the parts are such that seating of valve C does not have the effect of 130 causing piston M to cut off shell-bore r from the hollow plug P, and the latter being normally positioned to have its port f' register with passage b' fluid under pressure ascend-

ing this passage readily finds its way into said shell-bore under said piston.

Having thus described my invention, what I claim as new, and desire to secure by Letters 5 Patent, is—

1. The combination of a casing having an inlet, an outlet and a partition intermediate of the inlet and outlet provided with an aperture; an engineer's valve controlling a by-pass between the inlet and outlet of the casing below the partition therein, a valve for the partition-aperture, a cone suspended from the latter valve, a shell supported above the casing, a piston within the bore of the shell 15 in stem connection with the cone-supporting valve, and suitable means for admitting to said shell, below the piston, some of the volume of fluid under pressure that may pass either of the aforesaid valves.

2. The combination of a casing having an inlet, an outlet and a partition intermediate of the inlet and outlet provided with an aperture; an engineer's valve controlling a by-pass between the inlet and outlet of the casing 20 below the partition therein, a valve for the partition-aperture, a cone suspended from the latter valve, a shell supported above the casing, a piston within the bore of the shell in stem connection with the cone-supporting 25 valve, suitable means for admitting to said shell, below the piston, some of a volume of fluid under pressure that may pass either of the aforesaid valves, and a pair of pop-valves controlling a vent-port in the aforesaid shell 30 above said piston.

3. The combination of a casing having an inlet, an outlet and a partition intermediate of the inlet and outlet provided with an aperture; an engineer's valve controlling a by-pass between the inlet and outlet of the casing below the partition therein, a valve for the partition-aperture, a cone suspended from the latter valve, a shell supported above the casing, a piston within the bore of the shell in 35 stem connection with the cone-supporting valve, suitable means for admitting to the shell, below the piston, some of a volume of fluid under pressure that may pass either of the aforesaid valves, and a spring-controlled 40 plunger constituting a valve for an opening in the shell-top, a portion of this plunger being exposed to the fluid under pressure that may find its way through a port leading from the aforesaid casing into a chamber of said 45 shell.

4. The combination of a casing having an inlet, an outlet and a partition intermediate of the inlet and outlet provided with an aperture; an engineer's valve controlling a by-pass between the inlet and outlet of the casing below the partition therein, a valve for the partition-aperture, a cone suspended from the latter valve, a shell supported above the casing, a piston within the bore of the shell 50 in stem connection with the cone-supporting 55

valve, suitable means for admitting to said shell, below the piston, some of a volume of fluid under pressure that may pass either of the aforesaid valves, and a stop-cock arranged to permit of the pressure under said piston 70 being let off at will.

5. The combination of a casing having an inlet, an outlet and a partition intermediate of the inlet and outlet provided with an aperture; an engineer's valve controlling a by-pass between the inlet and outlet of the casing below the partition therein, a valve for the partition-aperture, a cone suspended from the latter valve, a shell supported above the casing, a piston within the bore of the shell 75 in stem connection with the cone-supporting valve, and a three-way stop-cock having its chamber portion in connection with a passage leading from the casing-outlet and that portion of said shell containing the piston. 80

6. The combination of a casing having an inlet, an outlet and a partition intermediate of the inlet and outlet provided with an aperture, an engineer's valve controlling a by-pass between the inlet and outlet of the casing below the partition therein, a valve for the partition-aperture, a cone suspended from the latter valve, a shell supported above the casing, a piston within the bore of the shell in 85 stem connection with the cone-supporting valve, a three-way stop-cock having its chamber portion in connection with a passage leading from the casing-outlet and that portion of the said shell containing the piston, a weight-controlled bell-crank fast to the plug 90 portion of the stop-cock, and a stop arranged to maintain the bell-crank in normal position.

7. The herein-described cut-off comprising a casing having an inlet, an outlet and a partition intermediate of the inlet and outlet provided with an aperture, an engineer's valve controlling a by-pass between the inlet and outlet of the casing below the partition therein, a valve for the partition-aperture, a cone suspended from the latter valve, a shell supported above the casing and having a top opening leading from a space in port connection with said casing, a piston in the shell having stem connection with the cone-supporting valve, a pair of pop-valves controlling 105 a vent-port in the shell above the piston, a stop-cock having the chamber portion thereof in connection with that portion of the shell containing the piston and a passage leading from the casing-outlet, and a spring-controlled 110 plunger constituting a valve for the shell-top opening. 115

In testimony that I claim the foregoing I have hereunto set my hand, at Milwaukee, in the county of Milwaukee and State of Wis- 120 consin, in the presence of two witnesses.

F. B. GIESLER.
